UNITED STATES PATENT OFFICE.

EDWARD W. STOCKLEY, OF PHILADELPHIA, PENNSYLVANIA.

FOLDING SCREEN.

1,118,069.

Specification of Letters Patent. Patented Nov. 24, 1914.

Application filed March 30, 1914. Serial No. 828,349.

To all whom it may concern:

Be it known that I, EDWARD W. STOCKLEY, a citizen of the United States, residing at Philadelphia, in the county of Philadelphia and State of Pennsylvania, have invented certain new and useful Improvements in Folding Screens, of which the following is a specification.

My invention relates to improvements in folding screens, the object of the invention being to provide a screen which may be positioned in rectangular form to provide a housing in which a baby-coach or other article may be located and which will effectively screen the occupant of the coach so that flies, mosquitos, and other insects cannot get into the housing.

A further object is to provide a screen of this character which consists of a top, sides, and ends hinged together so that either of the sides or ends may be utilized as a door to allow the baby-coach to be rolled into the housing and provide improved means for connecting the sections so that they may be securely locked together or folded into a compact shape.

A further object is to provide improved means for hinging the sections together with an improved arrangement of securing devices for holding the screen either in its normal or folded position, and when secured in the latter position, occupy but relatively small space in storing and shipping.

With these and other objects in view, the invention consists in certain novel features of construction and combinations and arrangements of parts as will be more fully hereinafter described and pointed out in the claims.

In the accompanying drawings: Figure 1 is a view in side elevation illustrating my improvements. Fig. 2 is a view in vertical longitudinal section. Fig. 3 is a top plan view. Fig. 4 is a fragmentary view in section on an enlarged scale on the line 4—4 of Fig. 3. Fig. 5 is a similar view on the line 5—5 of Fig. 3, and Fig. 6 is a perspective view showing my improved screen in its folded condition.

My improved screen consists of a top 1, sides 2, and ends 3, all of general rectangular form and each consisting of a metal frame with a screen preferably of wire netting secured thereto. While, of course, my invention is not limited to any particular shape of these sections, I preferably form

them as indicated to give to the screen when in its normal position, a greater length than breadth, so that while the top and ends are of the same dimensions, the sides are appreciably wider as clearly shown in Fig. 6.

The sides and ends are connected at their upper ends with the top 1 by means of hinges as will be hereinafter described, and at their lower ends they are connected by suitable fastening devices to hold the screen in rectangular shape. I have indicated as fastening devices, hooks 4 and eyes 5, and it is to be understood that any pair of these hooks may be disconnected from their eyes to release a side or end to allow a baby-coach indicated at 6 to be rolled into the screen after the child has fallen asleep.

The hinges above referred to for the different sections are provided in pairs, but are differently formed to allow the sections to fold flatly together as shown in Fig. 6. For example, the hinges 7 connecting one end section 3 with the top section 1, have their leaves 8 bent at right angles with the hinge pin 9 located at the upper end of the end section 3 in a plane slightly above the top 1. This is desirable because it is necessary when folding the end 3 upon the top 1 to leave a space between the end and the top for the accommodation of the side section 2. Also in order that the parts may snugly fit together, recesses 10 are located in the ends 3 to accommodate the upwardly projecting portion of the leaves as clearly shown in Fig. 4. The hinges 11 connecting the other end section 3 with the top 1, have one leaf 11^a bent at right angles and secured to top 1, the other leaf 12 being straight and secured to the end 3, this end being recessed as shown at 13 for the accommodation of the hinges. The hinge pins 14 of hinges 11 are located in a plane appreciably below the lower surface of top 1, so that this end section when folded, provides ample space between the same and the top for the other side section 2. The side sections 2 are connected to the top by ordinary leaf hinges 15, so that they can be swung directly against the top, one section folding onto the upper surface of the top, and the other side section against the bottom surface of the top, with the end sections 3 folded over the side sections as clearly shown in Fig. 6. When in this position, the sections are secured together by hooks 16 which are provided on the inner faces of the sides 2 and engage the

eyes 5 on the end sections, securely locking all of the sections against movement. A handle 17 is provided on one of the end sections, so that when the several sections are folded together, this handle serves as a convenient means of carrying the screen about.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

15 Having thus described my invention, what I claim as new and desire to secure by Letters Patent is:

1. A folding screen comprising a top, sides, and ends, said sides connected to the top and adapted to be folded against opposite sides of the top, said ends connected by hinges with the top, one of said ends having its hinge pin connection in a plane above the top a distance greater than the thickness of a side, and the other end section having its hinge pin connection in a plane below the top a distance greater than the thickness of

the other side section, substantially as described.

2. A folding screen comprising a top, 30 sides, and ends, said sides connected to the top and adapted to be folded against opposite sides of the top, said ends connected by hinges with the top, one of said ends having its hinge pin connection in a plane above 35 the top a distance greater than the thickness of a side, and the other end section having its hinge pin connection in a plane below the top a distance greater than the thickness of the other side section, said sections adapted 40 to be folded with the sides against opposite faces of the top and with the ends over the sides, fastening devices connecting the folded sections and holding them together, and a handle on one of said sections, substantially 45 as described.

In testimony whereof I have signed my name to this specification in the presence of two subscribing witnesses.

EDWARD W. STOCKLEY.
